MEMORANDUM DEVICE

Harry M. Burt, Cranston, R. I., assignor to Louis Karasik, New York, N. Y.

Application June 27, 1938, Serial No. 215,951

6 Claims. (Cl. 35—63)

This invention relates to improvements in a memorandum device to be mounted on a wall or other suitable support proximate a telephone, including for example, public telephone booths or 5 the like upon which memoranda may be made whereby said device is adapted to serve among other things as a deterrent to the tendency on the part of many persons to deface the walls and furniture near the telephone.

10 An important object of my invention is to construct a device of the class described so that the means for fastening the same to a wall or any other suitable support will be more or less concealed or relatively inaccessible to prevent the 15 ready removal thereof.

A further object of my invention is to produce a device of the class described in which a plate or card bearing an advertising legend may be mounted therein by means readily permitting 20 from time to time, the removal and replacement thereof by a plate having a different legend.

Still a further object is to provide in a device of the class described a surface upon which to make memoranda and from which the same 25 may be erased or wiped off with a damp cloth or the like.

Other objects and advantages of my invention will either become apparent or be specifically referred to in the following description thereof 30 written with reference to the accompanying drawing, illustrating by way of example, a preferred embodiment thereof and in which:

Figure 1 is an elevational view of a memorandum device embodying my invention, and having 35 portions broken away to show features of its construction;

Figure 2 is a view taken on the line 2—2 of Figure 1 and looking in the direction of the arrows;

40 Figure 3 is a bottom view of the device shown in Figure 1;

Figure 4 is a sectional fragmentary view taken on the center line of a device similar to that shown in Figure 1 but showing a modified means 45 for holding in place the advertising card means and means upon which to write memoranda, and at the same time conceal the manner by which said means may be removed;

Figure 5 is a sectional view of the device shown 50 in Figure 4, taken on line 5—5 and looking in the direction of the arrows; and

Figure 6 is a view of one form of device suitable for releasing the holding means shown in Figure 4.

55 Referring now to the drawing in which I illus-

trate a preferred embodiment of my invention, it will be seen that this device comprises a wooden frame having two side rails 10, each of which is provided with a tenon 11 formed on the upper end thereof and adapted to fit into suitable mortises formed in a top piece 12. A bottom rail 13 having a tenon 14 on each end thereof and adapted to fit respectively into mortises formed in the lower end of each of the side rails 10, completes the frame structure.

10 It will be understood that the frame may be made of any suitable material other than wood, as herein described, and indeed may be made of any suitable material in the form of a one piece structure such for example as by molding the 15

15 A dove-tail rabbet 15—16 is suitably cut in each rail 10 to provide a means for slidably receiving a pair of plates 17 and 18, for purposes 20 to be hereinafter described. The side edges of these plates are beveled at 19 to cooperate with, and so as to be retained in place by, the surface 25 of the rabbets.

As shown in Figure 2 a groove 20 is formed in the top piece 12 to provide a support for a cigar, 25 cigarette or pencil. This view also illustrates that the front surface of the bottom rail 13 is located in the same plane as the surface 16 of the rabbet 15—16 so that the flat plates 17 and 30 18 are adapted to enter and slide freely in the 30 rabbet from the bottom thereof to the top piece 12, and whereby the surface 21 of the plates is disposed in the same plane as the front face 22 of the side rails 10.

35 A projection 25 provided with a hole to accommodate a screw 26 is formed on the top piece 12 and a similar hole to accommodate a screw 27 is formed in the bottom rail 13, as shown in Figures 1 and 2, by which the device may be fastened to a suitable support.

40 The upper edge of the plate 18 is preferably notched out at 28 to form an opening for receiving a spring clip 29, having an extended portion 33 adapted to remain in contact with the back of the plate 18, and a front portion bent to form 45 a grip 31 adapted to yieldably hold a card against the front surface of the plate 18 upon which card memoranda may be noted as desired. The plate 17 is held against being slidably removed from the grooves by the lower edge of the top piece 12 50 serving as an abutment and by means of the upper edge of the plate 18.

55 On the back near the lower edge of the plate 18, projections 32 are formed which are adapted to fit into notches 33 formed in the bottom rail 55.

13. By means of screws 34 passing through the projections 32 and into the bottom rail the plate 13 is held in position. Being thus located the screws are usually below the level of the eye and 5 therefore inconspicuous and relatively concealed.

From the foregoing, it will be understood that any suitable advertising legend may be pasted, printed or otherwise displayed on the plate 17, and that such advertising legend may be changed 10 from time to time by removing the screws 34, withdrawing the plate 18 and thereafter removing the plate 17 and substituting therefor a similar plate carrying other advertising.

The lower part of the front surface of plate 18 15 is treated in any suitable way to form a surface 35 upon which matches may be struck, such for instance as having cemented or otherwise secured thereon a suitable composition or indeed roughening the surface of the plate itself. The remainder of the surface of the plate 18, is such 20 that memoranda may be written thereon and easily erased by any suitable means, such as by a damp cloth.

In the construction of my device, I preferably 25 mold the plates 17 and 18 of a suitable plastic material, but it will be understood that any other suitable material may be used, such for example as any suitable paper means or paper board having a suitably prepared surface.

30 Referring now to Figures 4 and 5, in which parts similar to those above described are indicated by similar characters, it will be seen that instead of the projections 32 and screws 34 for retaining the plate 18 in position, I provide means 35 entirely concealed behind the plates, such for example as a notch 38 formed in the back of the plate 18 adapted to cooperate with the upper end of a leaf spring 39 secured in any suitable way to the back of the lower rail 13 or confined between 40 said rail and the frame support. The front portion of the lower rail 13 over the hole 27 in the modification shown in Figure 4 is cut out as at 40 to provide a rectangular aperture through which a tool such as shown in Figure 6 may be inserted 45 from a point outside the frame, and by which the spring 39 may be pressed away from the plate 18 and out of engagement with the notch 38 and permit the same to be withdrawn. One advantage of this method of securing the plate 18 in 50 the device is that it is less obvious how the plate may be removed and particularly how the spring 39 may be moved to inoperative position and thus prevent the removal of the plates 17 and 18 by persons not authorized to do so. It will be understood 55 that the device shown in Figure 4 may be assembled by pushing the plates 17 and 18 into the grooves as above described until the spring 39 drops automatically into the notch 38, a position which may be described as their home position.

60 While I have described what now seems to be the preferred embodiment of my invention, it is conceivable that various modifications in the configuration, composition and disposition of the 65 component parts going to make up the same may occur to those skilled in the art, and that various changes in the form, proportion and minor details may be resorted to within the scope of my invention.

70 What is claimed is:

1. A memorandum device comprising in combination a pair of plates at least one of which is made of material from which memoranda recorded thereon may be erased, a frame therefor adapted to be mounted upon a support; said

frame having groove means for slidably receiving and retaining in place said pair of plates when the same are disposed edge-to-edge therein, and an aperture; and clamping means cooperating with the front surface of one of said plates disposed between the abutting edges thereof, in combination with means for holding said plates in position in said frame to prevent the withdrawal thereof and confine said clamping means between said plates, said holding means being concealed 10 behind one of said plates and comprising spring means mounted upon said frame adapted to be moved into inoperative position by an instrument inserted through said aperture. 5

2. A memorandum device comprising in combination a pair of plates at least one of which is made of material from which memoranda recorded thereon may be erased, a frame therefor adapted to be mounted upon a support; said frame having a top piece, two side rails and 20 groove means formed in said rails for slidably receiving and retaining in place said pair of plates when the same are disposed edge-to-edge there-between; and clamping means cooperating with the front surface of one of said plates disposed between the abutting edges thereof, in combination with means for holding said plates in position against said top rail to prevent the withdrawal thereof from between said side rails and confine said clamping means between said plates. 25

3. A memorandum device comprising in combination plate means including an area made of material from which memoranda recorded thereon may be erased, and a frame therefor adapted to be mounted upon a support; said frame having 35 means for receiving and retaining in place said plate means and an aperture; in combination with means for holding said plate means in position in said frame to prevent the withdrawal thereof, said holding means being concealed behind said 40 plate means and comprising spring means mounted upon said frame and movable into inoperative position only by means of an instrument inserted through said aperture. 45

4. A device of the class described comprising 50 plate means having a surface suitable for recording memoranda thereon and from which the same may be erased, in combination with means for mounting said plate means upon a support, said mounting means comprising a frame having a top piece adapted to serve as an abutment for said plate means, and a side rail depending from each end of said top piece provided with a groove open at the bottom between which said plate means is adapted to slide and be retained thereby with the front surface of said plate means and front surface of said side rails and a portion of said top piece disposed in a common plane, and means for retaining said plates in position against said abutment. 55

5. A device of the class described comprising 60 plate means having a surface suitable for recording memoranda thereon and from which the same may be erased, in combination with means for mounting said plate means upon a support, said mounting means comprising a frame having a top piece adapted to serve as an abutment for said plate means, and a side rail depending from each end of said top piece provided with a groove open at the bottom between which said plate 70 means is adapted to slide and be retained thereby with the front surface of said plate means and front surface of said side rails and a portion of said top piece disposed in a common plane, and means for retaining said plate means in position 75

against said abutment, said retaining means comprising a notch in the back of said plate means and a leaf spring mounted on said frame adapted to cooperate with said notch.

6. A device of the class described comprising plate means having a surface suitable for recording memoranda thereon and from which the same may be erased, and means for mounting said plate means upon a support; said mounting means comprising a frame having spaced groove

10

means between which said plate means is adapted to slide and be retained thereby, and an aperture; in combination with means concealed by said plate means for retaining the same in position, said retaining means comprising a notch in the back of said plate means and a leaf spring mounted on said frame adapted to cooperate with said notch and being operable from a point outside of said frame through said aperture.
